CALF WEANER

Wade P. Inabnit, Wilsall, Mont.

Application July 3, 1937, Serial No. 151,901

3 Claims. (Cl. 119—130)

This invention relates to weaners for calves, colts, and the like, and an object of the invention is to provide a device of this character which will be effective in preventing calves, colts or other animals from nursing the mother animal, and also to cause the mother animal to leave the nursing animal; together with improved means for fastening the weaner to the animal's head.

10 The invention together with its objects and advantages will be best understood from a study of the following description taken in connection with the accompanying drawings wherein:

Figure 1 is a side elevational view of the 15 weaner and showing the same applied.

Figure 2 is a front elevational view also illustrating the application of the weaner and

Figure 3 is a perspective view of the weaner.

Referring to the drawings by reference numerals it will be seen that the preferred embodiment of my improved weaner comprises a metallic strip 5 bent into arcuate form and having elongated pointed prongs or spurs 6 projecting outwardly therefrom in a substantially radial series.

20 At the ends thereof the strip 5 is pivotally connected to one end of metallic cheek straps 7 through the medium of pivot pins 8 engaging in openings provided therefor in the ends of the strip 5 and aligning with elected openings 9 arranged in series in the lower ends of the cheek straps whereby an adjustable pivotal connection between the strip 5 and the straps 7 is provided for.

25 Riveted to the inner side of the cheek straps 7 as at 10 and 11 respectively are complementary head straps 12 and 13 respectively. In the present instance the head strap 13 at its free upper end is provided with a buckle 14 for cooperation 30 with the free end 15 of the strap 12 for securing the ends of the straps 12 and 13 together at the top of the head of the animal.

35 A throat latch 16, in the form of a strap is provided to be passed around the neck and throat 40 of the animal as shown in Fig. 1 and opposite portions of the throat latch 16 work through loops 17 provided in one end of straps 18, 19. Straps 18, 19 are also provided with loops 20 through which the head straps 12, 13 extend, 45 and one of the guide straps, for example the guide strap 19 is provided at its free end with a buckle 21 for cooperation with the end 22 of strap 18 whereby said straps 18 and 19 may be adjustably fastened together across the forehead of 50 the animal.

For an intermediate portion of the throat latch 16, and the free end of the head strap 12 there is provided a guide 23 in the form of a strip of leather or other suitable material, the opposite end portions of which are folded inwardly toward one another and riveted to an intermediate portion of the strap to provide loop 24 for the latch 16 and loop 25 for the end 15 of strap 12.

Further a nose band 26 of metal is set into 10 arcuate form for disposition around the nose of the animal and at its respective opposite ends is riveted as at 27 to the lower end portions of the cheek straps 7. Secured to the inner side of the nose strap 26 by rivets or in any other suitable 15 manner, and as indicated generally at 28 is a pad 29 in the form of a strip of any suitable fabric.

The ends of the nose strap 26 are connected together through the medium of an adjustable jaw 20 strap 30 of leather or other suitable material and adapted to pass under the lower jaw of the animal.

The weaner strip 5 is normally and yieldably urged downwardly to assume a position across the 25 nose of the animal through the medium of a spring 31 that has an intermediate portion thereof looped about one of the pivots 8 and one end portion suitably anchored to the adjacent cheek strap 7, and the other end portion suitably engaged with the adjacent end of the weaner strip 30 5 as clearly shown in Fig. 3.

To secure the weaner strip 5 at the desired position of adjustment there is provided a strap 32 suitably secured at one end to the weaner 35 strip 5 intermediate the ends of the latter and having a free end cooperable with a buckle 33 suitably provided on an intermediate portion of the nose strap 26. The manner of applying the weaner to the head of the animal is thought to 40 be obvious and to be clearly illustrated in Figs. 1 and 2. With the weaner in position it will be apparent that the weaner strip 5, while not interfering with the ordinary feeding or drinking of the wearing animal will, upon attempt by the 45 wearing animal to nurse the mother animal and through the medium of the prongs or spurs 6 prod the mother animal and cause her to leave the nursing animal. Also with this device sucking will be prevented.

50 Further through the arrangement of cheek and head straps, throat latch, nose strap, and jaw strap, the device may be securely fastened in position on the head of the animal and will remain in proper position thereon notwithstanding 55

ing efforts on the part of the wearing animal to dislodge the same.

The advantages of the weaner will, it is believed, be apparent from the foregoing taken in connection with the drawings, and having thus described the invention,

What is claimed is:—

- 10 1. A calf weaner comprising a rigid U-shaped weaner strip for application to the nose of an animal, metallic cheek straps pivoted at one end to the ends of the weaner strip, a rigid nose strap extending between and secured at its respective opposite end to the cheek straps adjacent the ends thereof pivoted to the weaner strip, a chin strap connecting the ends of said nose strap, complemental head straps secured at one end to the metallic cheek straps, a pair of opposed complemental straps provided intermediate their respective ends with loops receiving the 15 cheek straps and complementarily provided each at one end with means for detachably securing said ends together across the forehead of an animal, said complemental straps having free ends provided with guide loops, and a throat latch in 20 the form of a strap having opposite portions threaded through said loops.
- 20 2. A calf weaner comprising a rigid U-shaped weaner strip for application to the nose of an animal, metallic cheek straps pivoted at one end to the ends of the weaner strip, a rigid nose strap extending between and secured at its respective opposite ends to the cheek straps adjacent the ends thereof pivoted to the weaner strip, a chin strap connecting the ends of said nose strap, complemental head straps secured at one end to the metallic cheek straps, a pair of opposed complemental straps provided intermediate their respective ends with loops receiving the cheek straps and complementarily provided each at one end with means for detachably securing said ends together across the forehead of an animal, 25 said complemental straps having free ends provided with guide loops, a throat latch in the form of a strap having opposite portions threaded through said loops, a spring device engaged with one end of one of said cheek straps and one end of the weaner strip at the pivotal connection between 30 said one end of said one cheek strap and said weaner strip for normally urging the latter to swing downwardly into a position across the nose and mouth of an animal, and interengaging means on said weaner strip and said nose strap for securing the weaner strip at the desired position of adjustment.

5 3. A calf weaner comprising a rigid U-shaped weaner strip for application to the nose of an animal, metallic cheek straps pivoted at one end to the ends of the weaner strip, a rigid nose strap extending between and secured at its respective opposite ends to the cheek straps adjacent the ends thereof pivoted to the weaner strip, a chin strap connecting the ends of said nose strap, complemental head straps secured at one end to the metallic cheek straps, a pair of opposed complemental straps provided intermediate their respective ends with loops receiving the cheek straps and complementarily provided each at one end with means for detachably securing said ends together across the forehead of an animal, 20 said complemental straps having free ends provided with guide loops, a throat latch in the form of a strap having opposite portions threaded through said loops, a spring device engaged with one end of one of said cheek straps and one end of the weaner strip at the pivotal connection between 25 said one end of said one cheek strap and said weaner strip for normally urging the latter to swing downwardly into a position across the nose and mouth of an animal, and interengaging means on said weaner strip and said nose strap for securing the weaner strip at the desired position of adjustment.

15 4. A calf weaner comprising a rigid U-shaped weaner strip for application to the nose of an animal, metallic cheek straps pivoted at one end to the ends of the weaner strip, a rigid nose strap extending between and secured at its respective opposite ends to the cheek straps adjacent the ends thereof pivoted to the weaner strip, a chin strap connecting the ends of said nose strap, complemental head straps secured at one end to the metallic cheek straps, a pair of opposed complemental straps provided intermediate their respective ends with loops receiving the cheek straps and complementarily provided each at one end with means for detachably securing said ends together across the forehead of an animal, 20 said complemental straps having free ends provided with guide loops, a throat latch in the form of a strap having opposite portions threaded through said loops, a spring device engaged with one end of one of said cheek straps and one end of the weaner strip at the pivotal connection between 25 said one end of said one cheek strap and said weaner strip for normally urging the latter to swing downwardly into a position across the nose and mouth of an animal, an adjustment strap secured at one end to said weaner strip intermediate the ends of the latter, and a buckle on the intermediate portion of said nose strap and with which the free end of said adjustment strap is cooperable for securing the weaner strip 30 at the desired adjustment, said weaner strip having prongs extending forwardly and radially therefrom.

35 WADE P. INABNIT.
